UNITED STATES PATENT OFFICE.

LOUIS V. ARONSON, OF NEWARK, NEW JERSEY.

DESIGN FOR A TOY.

Application filed May 29, 1924. Serial No. 9,743. Term of patent 7 years.

To all whom it may concern:

Be it known that I, LOUIS V. ARONSON, residing at Newark, in the county of Essex and State of New Jersey, have invented a new, original, and ornamental Design for Toy, of which the following is a specification, reference being had to the accompanying drawing, forming part thereof.

Fig. 1 is a front elevation and Fig. 2 is a side elevation illustrating the design.

I claim:

The design for a toy substantially as shown in the drawing.

LOUIS V. ARONSON.
